US00D817518S

(12) **United States Design Patent** (10) **Patent No.:** **US D817,518 S**
Singh (45) **Date of Patent:** **** May 8, 2018**

(54) **TRIM REVEAL EXTRUSION**

(71) Applicant: **Joshua George Singh**, Calgary (CA)
(72) Inventor: **Joshua George Singh**, Calgary (CA)
(**) Term: **15 Years**
(21) Appl. No.: **29/559,881**
(22) Filed: **Mar. 31, 2016**
(51) LOC (11) Cl. **25-02**
(52) U.S. Cl. **USPC D25/119**

(57) **CLAIM**

The ornamental design for a trim reveal extrusion, as shown and described.

DESCRIPTION

FIG. 1 is a perspective view of a trim reveal extrusion showing my new design; and,
FIG. 2 is an end view thereof.

The trim reveal extrusion is shown with a symbolic break in its length. The appearance of any portion of the trim reveal extrusion between the jagged break lines form no part of the claimed design.

1 Claim, 1 Drawing Sheet

FIG. 1

FIG. 2
